UNITED STATES PATENT OFFICE.

CARL BLANKENBURG, OF LEIPZIG-SELLERSHAUSEN, GERMANY, ASSIGNOR TO HUGO SCHNEIDER, ACTIENGESELLSCHAFT, OF LEIPZIG, GERMANY.

CENTRAL-DRAFT INCANDESCENT OIL-LAMP.

No. 927,769.

Specification of Letters Patent.

Patented July 13, 1909.

Application filed June 1, 1908. Serial No. 435,983.

To all whom it may concern:

Be it known that I, CARL BLANKENBURG, a subject of the King of Prussia, and resident of 13 Schützenhaus strasse, Leipzig-Sellershausen, in the Kingdom of Saxony, German Empire, have invented certain new and useful Improvements in Central-Draft Incandescent Oil-Lamps, of which the following is an exact specification.

10 This invention relates to improvements in incandescent oil lamps and is a further development of the invention described in the specification of application Ser. No. 393031 filed by Carl Blankenburg on the 16th of 15 September 1907.

20 The object of the present invention is to effect an improvement in the operation of such lamps by providing means for still further preventing heating of the outer wick tube.

25 The lamp is of the central draft type that is to say, air is led to the inner wick tube through a shaft or tube passing through the oil vessel.

30 The invention also comprises various improved details as hereinafter more fully explained with reference to the drawings and pointed out in the claims.

35 In the drawings Figure 1 is a view partially in vertical section through a central draft incandescent oil lamp according to the present invention, Fig. 2 illustrates an outside view of the air draft sieve, the parts being shown separated, Fig. 3 is a partial sectional view showing the parts assembled and the holding means employed for retaining them in the assembled position, Fig. 4 is a view similar to Fig. 2 showing a modified form of air draft sieve and gallery separate, Fig. 5 is 40 a view similar to Fig. 3 showing these parts in their assembled position.

45 In carrying the invention into effect according to the form shown in Fig. 1 oil is held in a container *a* which is provided with a central draft tube *b* to which air has access at the bottom as shown by the arrows. Around the central draft tube *b* which also forms the inner wick tube there is arranged the circular wick *c*. The wick *c* is caught by 50 a preferably perforated tube *d* which may be moved up and down by means of a rotatable finger piece *e*, the spindle of which carries a toothed wheel *g* gearing with a rack *h* connected to a pin *j* on the wick carrier tube *d*. 55 The outer wick tube *k* contacts with the wick

at its upper end and then widens downwardly after which it extends downwardly with constant diameter to terminate in the upper part of the font or oil-holder *a*. Within the widened part of the tube *k* there is arranged an insulating tube *m* surrounding the wick and forming with the tube *k* an insulating jacket extending over the exterior of the upper part of the wick from the point where the wick leaves the font or oil holder *a*. This air space may if desired be filled with any convenient heat insulating material. In the form illustrated however this air space is left free and the lower flange *n* of the insulating tube *m* is provided with small openings as shown so that air entering through the small hole *o* in the plug *p* of the oil holder can also pass into the air space between the outer wick tube and the insulating tube *m*.

50 The parts just described are supported in a nipple piece *q* which is screwed at *r* into the holder *a*. This nipple piece is also provided with a screw to which the outer air draft sieve *s* is attached. The outer air draft sieve will be more particularly described with reference to Figs. 2 and 3. The sieve *s* is connected by a bayonet joint to the usual gallery *u*. As in the form of my invention described in the application Ser. No. 393,031 55 the upper end of the wick tube *k* is protected from the flame by means of a ring *v* which does not contact with the upper end of the outer wick tube but comes in contact with the wick at a point above the end of the 60 wick tube. The air sieve *s* is also arranged to form a gage for the upper limit of the wick.

65 Formed in one with the gallery there is the usual hood piece *w* through the central opening in which the perforated air sieve *x* on the central tube *b* passes. A socket *y* is also provided for the purpose of holding the mantle supporting rod which is not illustrated in the drawings.

70 The operation of this lamp is as follows: Air enters the central draft tube *b* and also passes through the external air draft sieve *s* and mixes with the vapor rising from the wick. The vapor and air then pass in company through the opening of the burner hood *w* and burn with a blue flame. This blue flame is directed to some extent to play against the meshes of the mantle by means of the central sieve *x* which acts as a spreader.

In order to avoid the disadvantages which arise from heating of the wick the outer wick tube *k* is insulated from the inner wick tube by means of the insulating tube *m*.

5 In Fig. 2 there is illustrated in part sectional elevation the arrangement to the sieve *s* and gallery *u*, the parts being shown in the detached state. The sieve *s* consists of a lower part 6 and an upper part 7. A 10 ring 8 carrying bayonet joint connecting members or claws 13 is articulated to the sieve part 6 so as to be moved up and down. The articulating members consist of a bar 9 on which the ring 8 is fastened and which 15 slides in a guide 10 fixed on the wick tube *k* and a hooked lever 12 which is fixed on a spindle supported on the sieve part 6 and adapted to be rotated by a handle 11. The hooked lever 12 is adapted to engage between 20 two pins on the bar 9 and the hooked end of the lever catches one of said pins in the raised position of the ring 8 to hold said ring in an elevated position. In this raised position the lever 12 acts as a strut. The 25 upper sieve part 7 is provided with openings 14 in its outer ring part through which the bayonet joint members 13 pass. The cylinder gallery *u* is also provided with small openings or notches in its lower flange 15 to 30 permit of the bayonet joint members 13 passing above the flange 15. A shoulder 16 is also provided on the flange 15. The parts are assembled by passing the upper sieve part 7 over the bayonet joint members or 35 claws 13 and rotating till the said claws come to lie against the shoulders or projections 16.

Instead of arranging the common bayonet joint for the upper part 7 of the outer air 40 draft sieve and the gallery *u* in the manner illustrated in Figs. 2 and 3 I may effect this common jointing in the manner illustrated in Figs. 4 and 5. In this case the hook 13^a is fastened directly to the lower part 6^a of the 45 outer air draft sieve and the part 7^a of the gallery *u'* are arranged exactly as described above.

I claim:

1. In combination, a central draft tube, a wick around said tube, an outer wick tube 50 extending downwardly from near the upper end of said wick and widened, a tube within said widened part and surrounding the wick to form with the first mentioned outer wick tube, a heat insulating jacket, a ring around 55 the wick at its upper end above the end of the wick tube and a supporting member for said ring, said supporting member extending downwardly to be fixed to the first mentioned outer wick tube at its widened jacket 60 part.

2. In combination with an incandescent oil burner, a lower sieve part arranged around and below the burner, bayonet joint members articulated to said lower sieve part, an 65 upper sieve part having openings adapted to pass the bayonet joint members, and a cylinder gallery having a flange adapted to be passed over said bayonet joint members to simultaneously fix the gallery and upper 70 sieve part to said bayonet joint members.

3. In a central draft incandescent oil-lamp, the combination of a removable gallery for the lamp chimney, a separately removable air draft sieve part, a ring supporting said 75 gallery and sieve part, a common bayonet-joint connection for said parts to said ring, and means for raising and lowering said ring.

4. In a central draft incandescent oil-lamp, the combination of a removable gallery for 80 the lamp chimney, a separately removable air draft sieve part, a ring supporting said gallery and sieve part, a common bayonet-joint connection for said parts to said ring, and means for raising and lowering said ring, 85 comprising a guide bar fixed to said ring, a hooked lever engaging said bar to move it and hold it elevated.

In witness whereof I have hereunto set my hand in the presence of two witnesses.

CARL BLANKENBURG.
